US0D1101350S

(12) **United States Design Patent** (10) **Patent No.:** **US D1,101,350 S**
(45) **Date of Patent:** **** Nov. 4, 2025**

(54) **KIOSK FOR PROCESSING ELECTRONIC DEVICES**

(71) Applicant: **ecoATM, LLC**, San Diego, CA (US)

(72) Inventors: **Jarrod Hammes**, San Diego, CA (US); **John Silva**, San Diego, CA (US); **Ryan Baxter**, Las Vegas, NV (US); **Dario Miticocchio**, San Diego, CA (US)

(73) Assignee: **ecoATM, LLC**, San Diego, CA (US)

(**) Term: **15 Years**

(21) Appl. No.: **29/917,542**

(22) Filed: **Nov. 20, 2023**

Related U.S. Application Data

(62) Division of application No. 29/724,106, filed on Feb. 12, 2020, now Pat. No. Des. 1,010,271.

(57) **CLAIM**

The ornamental design for a kiosk for processing electronic devices, as shown and described.

DESCRIPTION

FIG. 1 is a top, front, right perspective view of a kiosk for processing electronic devices, showing our new design;

FIG. 2 is a bottom, front, left perspective view thereof;

FIG. 3 is a front elevation view thereof;

FIG. 4 is a back elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken lines shown in the drawings represent portions of the kiosk for processing electronic devices that form no part of the claimed design.

1 Claim, 4 Drawing Sheets
